MACHINE FOR PRINTING DIRECTLY ON
METAL OR GLASS AND THE LIKEFrederick Shurley, Salt Lake City, Utah, assignor
to Ceramic Machinery Distributors Limited,
Windsor, Ontario, Canada, a company incor-
porate of CanadaRefiled for abandoned application Serial No.
711,136, February 14, 1934. This application
December 30, 1935, Serial No. 56,833

14 Claims. (Cl. 101—38)

My invention relates to a machine for printing directly upon the surface of metal, glassware, pottery and the like, such as cans, bottles, jars, bulbs, and any description of containers, applicable to having thereon designs, trade-marks, or other insignia, whether ornamental or commercial, and which shall be permanent and add materially to the usefulness of the article so marked or decorated, and it has particular reference to a machine by means of which such marks, designs, or insignia may be printed in one or more colors.

The present application is a substitute for my application for Machine for printing directly on metal or glass and the like, Serial No. 711,136, filed February 14, 1934.

It is customary to print labels on paper or other sheet material and to affix such labels to the cans, bottles or other containers, but those can be removed easily and other labels applied thereto, thus making it unsatisfactory as well as expensive.

Among the salient objects of my invention are: to provide a machine which will receive, hold and print, in one or more colors, formed cans of any description, glass bottles, jars and containers of various materials in very much the same manner that printing presses receive, hold and print paper sheets, cards and the like and to do it more or less automatically, accurately and rapidly; to provide a machine of the character referred to in which there is a movable table for holding the dies, cuts, stencils or other printing means, whereby said table moves back and forth from a position in which it receives the ink or coating means to a position where the printing is done upon the article to be printed as said table moves in engagement therewith; to provide means for receiving and holding the article to be printed, such means being adapted, when the article to be printed is round, to revolve said article in synchronism with the movement of the printing table, whereby the printing is accomplished during the movement of the table to and from the article being printed; to provide holding means for the articles to be printed which use suction means for holding and releasing said articles; to provide in a machine of the character referred to means for inking or coating the rollers which apply said ink or coating to the printing mechanism and to also provide means whereby the inking rollers carrying the different colors will be automatically carried over the printing mechanism without engagement therewith except that the printing mechanisms will be

each engaged only by its color carrying roller, thus automatically applying two colors to two different and cooperating printing portions of the printing mechanism; to provide in combination with said printing machine means for printing bands around the articles being printed, said band printing means being mounted to automatically adjust their positions to the articles as said articles are turned; to provide in a machine of the character referred to a traveling table which carries one or more ink-applying platens and also printing mechanism to be inked, said table, platens and printing mechanism moving under ink-applying rollers yieldingly mounted above said table and adapted to be moved into and out of engagement with said platens and with the printing mechanism according to the colors carried thereby.

Other objects and advantages will be apparent from the following detailed description of one practical embodiment of my invention, taken with the accompanying four sheets of drawings, which I will now describe.

Figure 1 is a perspective view of a printing machine embodying my invention;

Figure 2 is an end elevation of said printing machine;

Figure 3 is a vertical, longitudinal sectional view taken through the machine on the line 3—3 of Fig. 4;

Figure 4 is a plan view of the machine on the line 4—4 of Fig. 3;

Figure 5 is an enlarged sectional view through one of the holding members;

Figure 6 is a similar view through the cooperating holding member;

Figure 7 is a fragmentary view in perspective of the working mechanisms located beneath the table;

Figure 8 is a side elevation of a banding mechanism for printing bands on the article being printed;

Figure 9 is an enlarged, fragmentary portion, of a banding mechanism;

Figure 10 is a perspective view of an improved mechanism for distributing and applying the ink, being a modified form of that shown in Fig. 1;

Figure 11 is a plan view of the modified form shown in Fig. 10;

Figure 12 is a sectional view showing a detail;

Figure 13 is a sectional view taken on the line 13—13 of Fig. 11; and

Figure 14 is a sectional view taken on the line 14—14 of Fig. 11.

Referring now in detail to the drawings, I will

describe the embodiment of my invention here shown for this purpose. Two side frame members 1 and 2 are connected by cross members 3, 4, 5, 6, 7, and 8, whereby a rigid frame structure is erected for holding the operating mechanisms. Mounted in the lower portion of said frame structure is a fixed board or table 9, supporting a motor M and a pump P, said motor M being adjustably held by means of the members 10 and 10' whereby it can be adjusted to regulate the tension of a driving belt 11. On the motor shaft are two driving pulleys, 12 and 14, the pulley 12 being connected through the belt 11 with a pulley 13, as seen in Fig. 1. The pulley 14 is connected through a belt 15 with a pulley 16 on the pump P, the latter being operated as a vacuum pump for purposes hereinafter referred to. Clutch means, designated 17, are shown for the purpose of connecting or disconnecting said pump at will. Fig. 4. The pump P is connected with a cross pipe 17', seen in Figs. 1 and 4, connected at its opposite end with a valve at 18, Fig. 1, connected with a pipe 19, to the ends of which are hose connections, as 20 and 21, which are in turn connected with vacuum cups or holding members 22 and 23, between which are held the article to be printed. Pulley 13 is mounted on shaft 24, turning in bearings 25 and 25', supported on the bed table 9, Figs. 1 and 7. Mounted on said shaft 24 is a sprocket 26 which, through a chain 27, drives a sprocket 28 on a shaft 32. A gear 29 is also mounted on said shaft 24 and meshes with gear 30' on shaft 32, on which shaft 32 are two clutch mechanisms, as 30 and 31. A sprocket 33, on shaft 32, is connected by means of sprocket chain 34 to sprocket 35, on shaft 39. The shaft 32 is supported at its opposite ends by means of bearings 36 and 37, supported in the frame structure. Also mounted on shaft 39 is a smaller sprocket 38 connected to a sprocket 40 by a sprocket chain 41, on shaft 42. The shaft 39 also carries a gear 43, which meshes with a gear 43', on shaft 44, supported in bearings at 45 and 46 in the frame structure as indicated Fig. 7. Slidably keyed to the shaft 44 is a gear 47, constituting means for operating a rack 49, on the under side of a movable table 48, adapted to be moved longitudinally back and forth, that is from its ink receiving position to its printing position. Said table 48 is provided with stops.

Positioned to engage with and operate a lever end 50, at the upper end of lever 51, said lever 50 being connected by means of a link 52 having a slotted head 53, having on one side a roller 55, positioned to be engaged by a cam 54 on shaft 42, Fig. 7. Connected with said lever 51 is also an arm 59 connected with a clutch shifting fork 59 for operating the clutches 30 and 31 to control the movement of the table 48. When clutch 31 is engaged, the rotation of gear 47 is reversed, thereby moving the rack 49 and the table 48 into inking position. As a means for manually moving said vertical lever 51 to control the direction of movement of the printing table 48, a handle 56 is pivotally mounted in the frame and connected by means of a rod 58 to said lever 51, as seen in Fig. 1. Gear 47 slidably keyed to shaft 44, is movable out of mesh with the rack 49, on the printing table, by means of a fork 61, on shaft 60, provided with two stop collars 64 and 65, thus making it possible to disconnect the printing table from the gear 47 so that said table can be moved by hand back and forth for any desired purpose. Said shifting shaft 60 is slidably mounted in two upright members 62' and 63' on

the side members 62 and 63, Fig. 7. A shaft is also mounted through the frame members 62 and 63, and is provided with a fork 66 for operating a clutch 68, on shaft 39, for disengaging the sprocket 38 from the shaft 39, at will. Said shifting shafts 60 and 67 are provided on their outer ends with suitable handles, as 66. Mounted on shaft 42 is a cam 10, engaged by a roller 71, on a lever 72, the upper end of which is connected with shaft 73. Shaft 42 is constantly driven and constitutes a means for arresting the forward movement of the printing table 48, by the operation of the cam 54 coming in engagement with roller 55 on link head 53, through which vertical lever 51 is moved to operate the clutches 30 and 31. As the cam 10, on shaft 42 is rotated therewith, it operates to rock shaft 73, which is connected by means of arms 78 and 79 at its opposite ends, and links 80 and 81, with the upright end members 74 and 75, slidably mounted on the base members 76 and 77, secured to the side frame members 1 and 2, as seen in Fig. 1. These end members 74 and 75 support a cross member 82 on which are mounted fittings for conducting paint to banding or striping mechanisms, as 83, through hose 84, see Figs. 2 and 8. In Fig. 8 is an enlarged view of one of these banding or striping mechanisms. Also supported between the end members 74 and 75 is a slotted cross member 85, adjustably secured in said members 74 and 75 by means of clips or brackets 86 and 87, in the slots, as at 88.

Referring to Fig. 8, the banding or striping mechanisms include a cylinder 83, secured to a base member 89, by means of supporting bands 91 and 92, said cylinder 83 being provided at one end with a hose connection 94, to receive hose 84, Fig. 3. The opposite end of said cylinder is provided with a screw cap 95, to which is properly secured a head 96, with a feed wheel 97, with a thumb or set screw 98 for adjusting the parts to regulate the flow of paint. The wheel 97 is in constant contact with the article to be banded or striped and serves to draw out the paint from the tube 83 and to apply it to said article. The base 45 plate 89 is slidably secured in a supporting base 100, having end pieces as 101 and 102, secured in place by screws 103. Two pins, as 104, are set in said end pieces and provided with springs, as 105, which engage the end plate 101 and also bear against the inside of the member 89, for yieldingly moving said member 89 and the banding tube 83 toward the work or article. The members 90 and 100 are provided with slot-ways, as at 107 and 108, to receive a through bolt 109, used for securing the banding mechanism as a whole to the slotted cross member 85, before described.

Referring now to Figs. 5 and 6, I have shown two vacuum cups or holding members 22 and 23. Vacuum cup or head 22 is secured to the end of a sleeve 114', in a bearing 115, which is slidably mounted in the frame member 1'. The position of this bearing can be varied by means of a screw 116, terminating in a base 117, and upward pressure is applied to said bearing 115 by means of a spring 118, held over a pin 119, set in the frame 1'. Mounted on said sleeve 114' is a sprocket wheel 110, held slidably in relationship by means of a set screw 110', said sleeve having a key-way or slideway therein so that it can be moved longitudinally through said bearing and said sprocket, said sprocket having thereon the sprocket chain 113 which also runs over sprocket 112, Figs. 1, 2 and 7, the slack in said chain 113

being taken up and regulated by means of a quadrant 114, on which is mounted a roller engaging with said chain in a well known manner.

Incased in the tube 114 is a hollow tube or pipe 120, having its end made to seat within the shank of the cup or member 22, and form a ground fit, as at 121. Pressure is provided by means of a spring 122, bearing against the opposite end of said tube or pipe 120, with a collar 123 on said pipe, and all enclosed in a closure cap or member 124, as clearly indicated in Fig. 5. The hose 20, hereinbefore referred to, is connected by means of the pipe fittings 125, for applying the suction created to the vacuum cup 22, the hose 15 being secured in place by clamp 126, or in any desired manner.

The vacuum cup 23 is pressed on to a sleeve or tube 127, in a bearing bushing 128, in a bearing member 129, slidably mounted in the frame member 2', in a similar manner to bearing 115. A sprocket wheel 131 is secured on said tube by means of a screw 130, said sprocket being driven by chain 132 from sprocket 133 on drive shaft 39. Slack in said chain 132 is taken up by a quadrant 23 134, with roller on, as before described, Fig. 4. The position of the vacuum cup or holding member is regulated by the screw member 135, seating in a base 136 on the bearing member 129. Upward pressure is kept constant by means of a spring 137, entered in a pin 138, which is pressed into the frame 2'. Both of the cups or members 22 and 23 are revolved in the same direction and at the same speed. Encased in the tube 127 is a pipe or tubular member 139 which seats at its 35 inner end in the cup body, as at 140, and is held constantly in its seat by means of a spring 141, bearing against a collar 142, and all enclosed in a cap 143, as before described for the other side of the holding mechanism. Hose 21 is secured to pipe fittings 144 by means of a clamp 145. Collars 147 and 148 are mounted on and keyed to the member 127, as seen in Figs. 6 and 2. A fork 149, forming the upper part of a lever 149', fits over the collar 147, as shown, and is operable 45 through a foot lever 146, connected therewith through a link 146', said levers being yieldingly held in normal positions as shown by means of a spring 150. If it is desired to move the cup 23 outwardly, it is only necessary to depress the foot pedal 146, which operates through the connections to lever fork 149 to move said tubular member 127 and said vacuum cup 23 outwardly, or to the right as shown in Figs. 2 and 6.

The carrier or printing table 48 is provided 55 along its opposite sides with rollers, as 154, positioned to run in the tracks 155 and 156, along the top of the frame structure.

In case it is desired to relieve the vacuum applied to the cups 22 and 23, the valve terminal at 60 18 is connected to a foot pedal 151, by means of a rod 152, on which is a coiled spring 153, normally holding said rod up and said valve at 18 closed.

Mounted on the top opposite sides of the table 65 48, are two cam rails, as 159 and 159' on one side and 160 and 160' on the opposite side, as will be understood from Fig. 3, showing how ink rollers are raised from one level to another as the table is moved back and forth. Two ink plates 70 157 and 158 are rotatably supported in suitable bearings 161 and 162, respectively, with ratchet portions 165 and 166, to be operated by means of an arm 164, connected with an operating rod 163, held in normal position by means of a coiled 75 spring 167. The plate is turned approximately

ninety degrees at each trip of the table 48. This is accomplished by the stop 168 engaging another stop 169. Thus with each trip of the printing table 48 the plates are given a partial turn to change their positions relative to the ink rollers 5 to engage the same intermittently as hereinafter described.

Mounted at opposite sides of the frame structure are two pairs of ink roller holders, 170 and 172, and 171 and 173, as seen in Fig. 1 one of 10 each side being seen in Fig. 3. The inking rollers 171 and 173 are mounted in suitable bearings to move up and down in said holders, with spring and screw means, as at 174, 175, 176, and 177, whereby said rollers are yieldingly held down in 15 their lower positions but can be raised by having their opposite ends, constructed to run on the side rails 159 and 160, whereby said rollers can be raised out of the plane of the plates 157 and 158 as the table 48 moves back and forth. This is 20 necessary when the plates have ink of different colors thereon, to prevent a roller of one color from engaging a plate having another color thereon.

Referring to Figs. 10 and 14 inclusive, I will 25 describe a slightly modified structure for handling the inking rollers. Mounted on the opposite frame members 1 and 2, are two supports or bearing holders, 180 and 181, for the bearing members 182 and 183, in which is mounted a 30 shaft 184, on which is an ink roller 185. The purpose of this ink roller is to engage with roller 186, which receives ink from the reservoir 187, and to receive therefrom a supply of ink which it transfers to the plate 157 as it moves thereunder. Roller 177 is then inked from said plate with the color of ink applied to that particular plate. The roller 185 and its shaft 184 have the wheels 188 thereon in position to run on the tracks 159 and 160, respectively, and also serves to rotate said roller 185 and distribute the ink upon the plate. The ink reservoir is designated 189, and its ends are formed into bearings 190 and 191 to hold the ends of the roller 186. An even flow of ink to the roller 186 on the ink plate 192, 45 is made possible by adjustment screws as 193.

In Figure 13, the rollers are shown in their normal positions, but as the table 48 moves forwardly, the rollers will follow on the rail or track 160 and drop down and roller 184 will distribute 50 ink on the plate 157, thus furnishing a supply of ink to said plate for roller 177, which in turn will ink the printing mechanism, or that portion thereof to receive its color of ink.

In Fig. 14, as the table 48 moves backward to 55 the end of its travel, the roller 184 is in contact with roller 186, the supply roller, and as the wheels 188 follow the side rails or tracks 160, the rollers 184 and 177 will return to the positions as shown in Figure 13 and finally to the distributing position. The roller 186 is rotated by means of an arm 195, Fig. 12, coming in engagement with a stop 198 as table 48 moves forward. Keyed to the roller and shaft 186 is a ratchet mechanism 197 and a pawl 196, for operating the roller 186 60 intermittently as the printing table moves forwardly and backwardly.

Thus I have provided a mechanism by means of which an article can be held in a printing position, and a table movable back and forth with 70 printing means thereon to be applied to said article, moves to an inking position and then to a printing position where the imprint is made upon the article being held. If the article is round, it is so mounted and held that it will revolve 75

as the printing table moves in engagement therewith. I have also provided adjustment means whereby said holding members for the article to be printed can be adjusted laterally, vertically 5 in the embodiment illustrating the invention. The printing mechanism is designated F on the carrier table 48 and this, of course, can be any suitable holding frame and any combination of design or other data or insignia to be printed on 10 the article. The holding members are movable to receive and hold the article and this is accomplished by the foot lever 146 and its connections with lever 149 and 149'. I have also shown the holding members in the form of vacuum cups, 15 with means for applying suction thereto to assist in holding the article therebetween, although it will be understood that these holding members can be made otherwise to clamp the article therebetween and to this end they are normally urged 20 toward each other by the lever 149 and its spring 150.

It will be understood that the motor M drives the operating mechanism for moving the carrier table 48 back and forth in the manner described; 25 that the ink plates and the distributing rollers operate as said table moves under said rollers and that the ink applying rollers are moved up and down by the varying tracks or rails 159 and 160, as before described, so as to apply different 30 colors of ink to different portions of the printing means on the carrier table 48.

While I have shown and described one practical embodiment of my invention, I am aware that many changes in the details of construction 35 and arrangement can be made therein without departing from the spirit thereof, and I do not, therefore, limit my invention to the showing made, except as I may be limited by the hereto appended claims constituting a part of 40 this application.

I claim:

1. A machine for printing on articles of glass, pottery and the like and including in combination a supporting structure, means thereon for 45 receiving and holding an article to be printed, a printing table with printing means thereon, means for moving said table and printing means into and out of a printing position, said printing means engaging said article as said table is moved into printing position, and means for applying ink to coextensive but different portions of said printing means seriatim during its movement in one direction.

2. A machine for printing on articles of glass, 55 pottery and the like and including in combination a supporting structure, means thereon for movably holding an article to be printed, a printing table with printing means thereon and movable back and forth for engagement with said article, means for moving said table, and ink applying means for applying ink to coextensive but different portions of said printing means on said table seriatim.

3. A machine for printing articles of glass, 65 pottery and the like and including in combination a supporting structure, means thereon for receiving and rotatably holding an article to be printed, a printing table with printing means thereon movable into engagement with a surface 70 on said article as the latter turns, means for moving said table and printing means, and ink applying means for applying ink to coextensive but different portions of said printing means on said table seriatim.

4. A machine for printing on articles of glass,

pottery and the like and including in combination a supporting structure, means thereon for receiving and holding in printing position an article to be printed, a printing table with printing means thereon and movable back and forth 5 in a horizontal course of travel, means for moving said table and printing means back and forth, means for applying ink to coextensive but different portions of said printing means on said table seriatim as it moves in one direction, and means whereby said article and the printing means on said table are moved together during the movement of said table back and forth on its course of travel.

5. A machine for printing on round articles 15 of glass, pottery and the like, and including in combination a supporting structure, means for rotatably holding the article to be printed, a carrier table with printing means thereon movably mounted on said structure, means for moving 20 said table and printing means back and forth in proximity to said article, whereby said article is engaged by and revolved with the movement of said table and printing means, and means for applying ink to coextensive but different portions 25 of said printing means seriatim during its movement in one direction.

6. A machine for printing on round articles of glass, pottery and the like and including in combination a supporting structure, means for rotatably holding the article to be printed, a carrier table with printing means thereon movably mounted on said structure, said printing means being adapted to be moved into engagement with said article with a rolling motion of the article, means for moving said table and printing means back and forth on a horizontal way, and means for applying ink in different colors to coextensive but different portions of said printing means seriatim. 40

7. In a machine of the character referred to, means for holding an article by its opposite ends, said means being revoluble, a carrier table with printing means thereon movable in proximity to said article, whereby the printing means engages 45 and turns said article in printing thereon as said table is moved, means for moving said table back and forth, means for applying ink to coextensive but different portions of said printing means seriatim as it moves in one direction, and means 50 for operating said holding means to open and close the same to receive the article to be printed.

8. A machine for printing directly on round articles of glass and the like and consisting of a supporting structure, two axially spaced 55 holding members revolubly mounted, one of said members being movable axially to close upon the article to be printed, means for revolving said holding members, means for adjusting said members together laterally, a printing mechanism movable into printing engagement with said article between said holding members, the engagement of said printing mechanism with said article being synchronized with the turning of said article, whereby the printing is done 60 during the turning thereof, and means for applying ink to coextensive but different portions of said printing mechanism seriatim.

9. A machine for printing articles of glass, pottery and the like and including a supporting 70 structure, two holding members mounted thereon and spaced axially to receive therebetween the articles to be printed, one of said members being movable axially, said members being in the form of vacuum cups, means for applying suc- 75

tion to said members to assist in holding the article therebetween, said holding members being adjustably mounted for adjustment laterally, a carrier table movable back and forth in proximity to said article and said holding members, means for moving the same, printing means on said table and positioned to be moved into printing engagement with said article between said holding members, and means for applying ink to said printing mechanism.

10. A machine for printing round articles of glass, pottery and the like and including in combination a supporting structure, two holding members revolubly mounted thereon and spaced axially to receive therebetween an article to be printed, said members being in the form of vacuum cups, means for applying suction to said cups, means for revolving said holding members and said article, a carrier table movable back and forth in proximity to said article, means for moving the same, printing means on said table, means for applying ink to said printing means, and means synchronizing the movement of said table and said printing means and the turning of said article to successfully print said article during the turning thereof in engagement with said printing mechanism.

11. In a printing apparatus, a printing member, means to reciprocate said member in a predetermined path, and a plurality of inking means to respectively apply ink to different portions of said printing member during its movement in one direction. 5

12. In a printing apparatus, a printing member, means to reciprocate said member in a predetermined path, and a plurality of inking means spaced along one end of said path to respectively apply ink to different portions of said printing member. 10

13. In a printing apparatus, a printing member, means to reciprocate said member in a predetermined path, and a plurality of inking means 15 to respectively apply ink to different portions of said printing member seriatim during its movement in one direction.

14. In a printing apparatus, a printing member, means to reciprocate said member in a pre- 20 determined path, and a plurality of inking means spaced along said path to respectively apply ink to different portions of said printing member seriatim during its movement in one direction.

FREDERICK SHURLEY.
